US0D1033667S

(12) **United States Design Patent** (10) Patent No.: **US D1,033,667 S**
(45) Date of Patent: ** Jul. 2, 2024

(54) **BELLY MASSAGER**

(71) Applicant: **Sichuan Qianli-beoka Medical Technology Inc.**, Sichuan (CN)

(72) Inventor: **Wen Zhang**, Chengdu (CN)

(73) Assignee: **Sichuan Qianli-beoka Medical Technology Inc. (CN)**

(**) Term: **15 Years**

(21) Appl. No.: **29/831,341**

(22) Filed: **Mar. 18, 2022**

(30) **Foreign Application Priority Data**

Sep. 27, 2021 (CN) 202130641388.4

(51) **LOC (14) Cl.** **24-01**

(52) **U.S. Cl.** ..... **USPC** **D24/215**

(57) **CLAIM**

The ornamental design for a belly massager, as shown and described.

DESCRIPTION

FIG. 1 is a front perspective view of the belly massager showing my new design;

FIG. 2 is a front elevational view thereof;

FIG. 3 is a back elevational view thereof;

FIG. 4 is a right elevational view thereof;

FIG. 5 is a left elevational view thereof;

FIG. 6 is a top plan view thereof; and,

FIG. 7 is a bottom plan view thereof.

The broken lines shown in the figures are for the purpose of illustrating portions of the belly massager, which form no part of the claimed design.

1 Claim, 7 Drawing Sheets
